PROCESS FOR REMOVING MERCAPTAN SULFUR WITH AN ORGANIC PHOSPHITE

William L. Fierce, Crystal Lake, and Walter J. Sandner, Carpentersville, Ill., assignors to The Pure Oil Company, Chicago, Ill., a corporation of Ohio

No Drawing. Application November 18, 1957
Serial No. 696,971

14 Claims. (Cl. 208—237)

This invention relates to improving the odor and minimizing the corrosiveness of petroleum fractions. It is more specifically concerned with the substantially complete elimination of mercaptan-sulfur from mercaptan-containing petroleum fractions.

According to this invention, the substantially complete reduction of mercaptan-sulfur in petroleum distillates can be effected by intimately contacting the mercaptan-containing petroleum distillate, which is substantially free from dissolved or absorbed oxygen, with an organic phosphite having the general formula,

where R, R' and R'' are selected from the group consisting of alkyl and cycloalkyl constituents, which provide organic phosphites soluble in light petroleum distillates, in an amount sufficient to effect the removal of said mercaptans, but not less than about 20 mols weight of organic phosphite per mol of mercaptan sulfur in the petroleum distillate being treated, at a temperature within the range of about 50° to 200° F.

The presence of mercaptans in low- and middle-boiling petroleum hydrocarbon products, such as gasolines, naphthas, kerosines and fuel oils, has a number of disadvantages. In gasolines and naphthas, the presence of 0.005 weight percent of mercaptan sulfur, and even as little as 0.002 weight percent, produces undesirable odors in the petroleum products. In excess of about 0.005 weight percent of mercaptan sulfur imparts undesirable corrosiveness to gasolines. Aryl thiols such as thiophenols and its homologs present in gasolines, kerosines, fuel oils and the like have an adverse effect on the storage stability of these petroleum products. In addition, mercaptans have an antagonistic influence on the lead susceptibility and octane rating of gasolines. It is therefore evident that these and other disadvantages make it important that mercaptans be eliminated from petroleum products of this nature.

Treating processes which are employed in the refining of mercaptan-containing gasolines in general fall into two broad classes:

(1) Those which chemically convert the mercaptans to other compounds such as disulfides, e.g., doctor-treating process, copper chloride, hypochlorite, lead sulfide, and other oxidative processes; and

(2) Those which extract mercaptans, e.g., caustic scrubbing, Shell Solutizer process, Pure Oil Mercapsol process, and Atlantic Unisol process.

Unfortunately, however, these processes are not free from disadvantages which arise from their use. For example, in the former type of process wherein the mercaptans are chemically converted to disulfides an undesirable result arises from the adverse effect of disulfides on the lead susceptibility of gasolines. While the extraction of mercaptans with caustic solutions, with or without solubility promoters, does not result in the pro-

2

duction of disulfides in the finished gasolines, this type of process is limited with regard to the final mercaptan-sulfur content which can be produced in the finished gasolines or other petroleum product which is treated. Although total sulfur reduction can be produced in various acid, clay and catalytic treating processes, a large capital expenditure is required to provide adequate commercial installations.

It is therefore an object of this invention to provide 10 a process for the conversion of mercaptans to innocuous materials which can be readily removed from the gasoline or other petroleum distillate treated, if desired. It is a further object of this invention to provide a chemical treating process for the substantially complete removal 15 of mercaptan-sulfur from petroleum fractions and the elimination of unpleasant odors from the treated product. Another object of this invention is to provide a treating process which minimizes the mercaptan-sulfur content of petroleum distillates without increasing the 20 disulfide-sulfur content of the treated gasoline. It is a further object of this invention to provide a treating process for the substantially complete removal of mercaptans from distillates by employing an economical process utilizing conventional petroleum refinery equipment. These and other objects will become more apparent from the following detailed description of this 25 invention.

According to this invention, the substantially complete reduction in the mercaptan-sulfur content of a low- or 30 middle-boiling petroleum fraction can be economically carried out without increasing the disulfide-sulfur content of the treated petroleum feed-stock by intimately contacting a mercaptan-containing petroleum fraction, such as naphtha, gasoline, kerosine, or fuel oil which is 35 substantially free from dissolved or adsorbed oxygen, with an organic phosphite having the general formula:

where R, R' and R'' are aliphatic or alicyclic substituents having 1 to 15 carbon atoms per molecule which provide an organic phosphite soluble in a naphtha or petroleum fraction. Sufficient amounts of the selected 45 organic phosphites to sweeten the fraction, in excess of about 20 mols of phosphite per mol of mercaptan sulfur contained in the petroleum fraction being treated, are incorporated in the mercaptan-containing petroleum 50 feed-stock, and the mixture is maintained in intimate contact for a time sufficient to effect the substantially complete reduction of the mercaptan-sulfur content of the petroleum fraction treated in accordance with this invention. Because the organic phosphites employed are 55 completely soluble in the petroleum distillate being treated, it is only necessary to employ mechanical mixing during the introduction of the phosphite treating agent. When the phosphite treating agent is completely in solution, it is only necessary to retain the admixture in a 60 quiescent state to effect the reduction of the mercaptan-sulfur content of the gasoline. The processing can be carried out at relatively low temperature, generally at temperatures within the range of about 50° F. up to about the boiling point of the fraction being treated.

The naphtha or other petroleum fraction treated must 65 be substantially free from dissolved oxygen in order to successfully carry out the process of this invention. Generally petroleum products, which are treated in accordance with this invention, immediately after separation from the crude petroleum oil are substantially oxygen-free. Products, however, which have been in storage and exposed to air prior to processing will contain amounts

of free oxygen absorbed therein which will deleteriously affect the efficiency of the process of this invention. Accordingly, stored products must be purged with an inert gas such as nitrogen, flue gas, dry normally gaseous hydrocarbons, or other similar substances, in order to deaerate or deoxygenate the petroleum-derived feed stock prior to treating to effect the reduction of mercaptan sulfur content. Other deaeration techniques can also be used such as contacting the oxygen-containing feed stock with an oxygen susceptible reagent such as metallic copper. Certain petroleum products such as straight-run naphthas, and cracked gasolines are susceptible to peroxidation. It is preferred that the straight-run products, which are subsequently to be treated in accordance with this invention, be purged of any free oxygen prior to being sent to storage and that the purged petroleum product be stored in facilities which provide an inert gas blanket in order to preclude the exposure of the product to air.

To determine if deaeration or deoxygenation is required, a sample of the suspected free oxygen-containing, feed stock can be purged with nitrogen and the gaseous effluent passed through an alkaline solution of pyrogallol to observe whether any darkening of the solution which is an indication of the presence of free-oxygen occurs. Another technique involving a modified Winkler procedure, which can be used, is described in *Analytical Chemistry* 28 (9), 1490, September 1956.

In addition other qualitative techniques for determining the presence of dissolved or absorbed oxygen will be apparent to those skilled in the art.

To facilitate the handling of the treating agent, it is preferred that a liquid organic phosphite soluble in naphtha or petroleum fraction be employed. In the alternative, however, soluble solid organic phosphites are also effective and can be employed if desired. In this event, it may be preferred to utilize a petroleum fraction concentrate of the selected organic phosphite. Examples of organic phosphites which are effective for the removal of mercaptans from petroleum fractions include but are not limited to trimethyl phosphite, triethyl phosphite, tri-n-propyl phosphite, tri-2-propyl phosphite, tributyl phosphite, triisobutyl phosphite, triamyl phosphite, trihexyl phosphite, tri-2-ethylhexyl phosphite, triisooctyl phosphite, tricyclohexyl phosphite and others. It is to be noted that in carrying out the treating process of this invention triaryl phosphites and other related compounds, such as the alkyl and aryl phosphates, are ineffective for reducing the mercaptan-sulfur content of a petroleum fraction.

To effect the reduction of the mercaptan-sulfur content in the hydrocarbon fraction which is being treated, the selected phosphite and the petroleum fraction containing mercaptans are intimately mixed and either allowed to stand at ambient temperatures for periods up to several days, or heated to temperatures about as high as the boiling point of the petroleum composition being treated for 0.5 to 10 hours. In the former instance a convenient method of treating consists of introducing a sufficient amount of the selected organic phosphite into a storage facility which is preferably one in which the mercaptan-containing petroleum fraction is contained. A mixing device installed in the storage facility is employed to effect the intimate admixing of the treating agent and the petroleum fraction. After the treating agent has been dissolved in the petroleum fraction to be treated, the mixing can be stopped and the solution allowed to remain at rest until the desired reduction in mercaptan sulfur content of the treated petroleum fraction is effected. If, on the other hand, it is preferred that the treating step be carried out at an elevated temperature in order to facilitate the treatment, conventional refining equipment suitable for contacting the treated petroleum fraction at an elevated temperature, in which an intimate admixing of the treating agent and the petroleum feed stock can be carried out, is used.

Although the instant process has application in the re-

fining of a number of light petroleum fractions, it is preferably employed in the manufacture of specialty naphthas which must conform with rigorous specifications regarding odor and mercaptan-sulfur content. In the event that gasolines or petroleum fractions intended for use as gasoline blending components are to be treated, the reaction products formed during the course of the treating process can remain in the treated gasoline because the products so formed are soluble in gasoline, are non-corrosive, and act as pre-ignition suppressers on the combustion of gasoline during use. Because the products contained in the petroleum fraction treated in accordance with this technique are substantially innocuous, it may be satisfactory, even when treating specialty naphthas to substantially reduce the mercaptan-sulfur content, to permit these products to remain in the naphtha. In the event, however, that it is desired to separate the treated naphtha from the products resulting from the treating step, simple distillation can be utilized by employing an organic phosphite so selected that it and the reaction product formed by it during the course of the treating step boil either below or preferably above the boiling range of the finished naphtha. The selected organic phosphite is added to the mercaptan-containing naphtha and after the treating step is completed, the resulting mixture is distilled so that the phosphorus-containing reaction products are separated either by being distilled first from the naphtha, or by being left in the bottoms from the distillation of the mixture.

The amount of organic phosphite employed in reducing the mercaptan-sulfur content of the petroleum fraction being treated will, in general, depend upon the amount of mercaptan which is in the petroleum feed-stock. It has been found that large molar excesses of the selected organic phosphite are required in order to effect a substantial reduction in the mercaptan-sulfur content of the treated feed-stock. The amount of mercaptan present in various hydrocarbon compositions often is small, frequently less than 0.10% by weight. Accordingly, it would be expected that only small amounts of the organic phosphite would be necessary. It has been found, however, that amounts substantially in excess of equimolar amounts of the treating agent and mercaptan must be employed. In general, an excess of about 20-40 times the number of mols of mercaptan sulfur present in the feed stock being treated are required. The exact amount required can be determined by experimentation employing small samples of the feed-stock to be treated. Accordingly, a ratio of about 20-40 mols of treating agent per mol of mercaptan-sulfur in the petroleum fraction being treated is ordinarily used, but in some instances amounts in excess of this range of treating agent may be required.

Various qualitative and quantitative methods are available for determining the presence and/or concentration of mercaptans in the petroleum fraction to be treated. Mercaptans can be detected by the well-known "doctor test," or by contacting the selected sample with a solution of sodium nitroprusside and a sodium hydroxide solution. The development of a purple color indicates the presence of mercaptan. The usual quantitative methods consist in titrating mercaptans with silver nitrate or ammoniacal copper sulfate solutions. A number of these techniques are outlined in a discussion of analytical methods and details by Kalichevsky in "Sweetening and Desulfurization of Light Petroleum Products," *Petroleum Refiner*, 29 (12), pp. 97 et seq.

In testing the treated product to determine the effectiveness of the treat, a sample of the finished product is distilled at atmospheric pressure and the distillate recovered in 10% cuts. This technique is necessary because the desired phosphite treating agent interferes with the doctor test.

Compositions especially adaptable to treatment by the process of this invention are petroleum fractions boil-

ing up to about 750° F. at atmospheric pressure. These include light distillates, such as industrial petroleum naphthas and solvents; gasoline-type motor fuels and motor fuel blending components; kerosines, and the middle distillates, such as diesel fuels, heater and furnace oils; etc.

The following examples demonstrate the effectiveness of this invention.

A plurality of samples of a low-sulfur naphtha derived from a Mid-Continent crude, having a ASTM boiling range of 111° F. I.B.P. to 414° F. E.P. containing 0.022 weight percent mercaptan-sulfur, and having a poor odor, were processed employing a variety of treating agents as well as different manipulative techniques. The samples after treatment were analyzed for mercaptan-sulfur by distilling the samples and subjecting the distillate to the "doctor" test. In addition, the odors were evaluated by an organoleptic panel of three men for the presence of odor. The samples tested and the results obtained are tabulated in Table I.

Table I

Sample No.	Phosphorus Compound Used	Moles Phosphorus Compound Per Mole Mercaptan	Vol. Percent Phosphorus Compound in Naphtha	Days Stored at Room Temperature	Other Treatment (See Notes)	Odor Evaluation	Wt. Percent Mercaptan Sulfurs	Doctor Test
1.	none	0.0	0.0			9	0.022	Sour.
2.	Tributyl Phosphite	6.7	1.0	4		8	0.016	Do.
3.	do	33.5	5.0	4		6	<0.002	Sweet.
4.	do	33.5	5.0	4	(a)	6	<0.002	Do.
5.	do	33.5	5.0	1	(b)	6		
6.	do	33.5	5.0	0		8	0.017	
7.	do	33.5	5.0	0	(c)			Sour.
8.	do	33.5	5.0	0	(d)			Do.
9.	do	67.0	10.0	0	(d)			Do.
10.	do	33.5	5.0	1				Sweet.
11.	do	26.8	4.0	2				Sour.
12.	do	20.1	3.0	8				Sweet.

15.	do	33.5	5.0	7	(f)			Sour.
16.	Triethyl Phosphite	31.8	3.0	3				Sweet.
17.	do	21.2	2.0	3				Sour.
18.	Tributyl Phosphate	33.3	5.0	14			0.018	Do.
19.	Tri-o-Tolyl Phosphate	29.7	5.0	14			0.011	Do.
20.	Triphenyl Phosphite	33.7	5.0	14			0.015	Do.

^a The solution of naphtha and phosphite was refluxed for five hours and then allowed to stand at room temperature for 4 days.

^b The solution of naphtha and phosphite was refluxed for 22 hours and then allowed to stand at room temperature for one day.

^c The solution of naphtha and phosphite was distilled immediately after mixing.

^d The solution of naphtha and phosphite was refluxed for 5 hours and then distilled.

^e The naphtha was purged thoroughly with nitrogen to remove air before treatment and stored under nitrogen.

^f The naphtha was purged with oxygen before treatment and stored under oxygen.

From the data tabulated in Table I the unusual or unexpected results produced by the process of this invention are readily seen, whereby doctor-sweet products are produced employing several non-aromatic phosphite treating agents. It is to be noted that while one would expect equimolar amounts of phosphite and mercaptan sulfur to effectively function to convert the mercaptan sulfur to an innocuous phosphorus- and sulfur-containing compound, these amounts are not operative. In contradistinction, it is necessary to have a substantial excess of organic phosphite in order to reduce the mercaptan-sulfur content of the petroleum feed stock to a substantial degree. In addition, it is to be noted that the process of this invention will not operatively function employing triaryl phosphites as is demonstrated by the use of triphenyl phosphite. In addition, analogous phosphorus compounds, such as the organic esters of phosphoric acid, viz., phosphates, also failed as agents for substantially reducing the mercaptan-sulfur content of the petroleum fraction treated. It is to be noted that in these instances neither the aliphatic, alicyclic nor aryl phosphates had utility for reducing the mercaptan content of the feed stock. The feature of employing an oxygen-free feed stock is also illustrated by the tabulated data.

It will be evident to one skilled in the art to which this invention pertains that modifications and variations can be made in the manipulative treating process described in the illustrative embodiment without departing

from the scope of the instant invention. Accordingly, the instant invention, which is concerned with the substantial reduction in the mercaptan-sulfur content of a petroleum fraction by contacting the fraction with an organic phosphite in amounts and for a time sufficient to produce a treated fraction substantially free from mercaptan sulfur, is limited only in the manner specifically set forth in the appended claims.

What is claimed is:

- 10 1. A process for substantially reducing the mercaptan-sulfur content and odor of a mercaptan-containing petroleum fraction which is substantially free from dissolved oxygen, which comprises intimately contacting said fraction with an organic phosphite from the group consisting of alkyl and cycloalkyl phosphites which is soluble in said hydrocarbon feed employing sufficient amounts not less than about 20 mols of phosphite per mol of mercaptan-sulfur and for a time sufficient to reduce the mercaptan-sulfur content of said fraction to 20 produce a doctor sweet product.

- 15 2. A process for substantially reducing the mercaptan-sulfur content and odor of a mercaptan-containing petroleum fraction which is substantially free from dissolved oxygen, which comprises intimately contacting said fraction with an alkyl phosphite which is soluble in said petroleum fraction, employing sufficient amounts not less than about 20 mols of phosphite per mol of mercaptan sulfur and for a time sufficient to produce a doctor sweet product.
- 50 3. A process for substantially reducing the mercaptan-sulfur content and odor of a mercaptan-containing petroleum fraction which is substantially free from dissolved oxygen, which comprises intimately contacting said fraction with an alkyl phosphite which is soluble in said petroleum fraction, employing sufficient amounts not less than about 20 to 40 mols of phosphite per mol of mercaptan sulfur and for a time sufficient to produce a doctor sweet product, said contacting being carried out at a temperature within the range of about 50° F. to the initial boiling point of the petroleum fraction.
- 55 4. A process in accordance with claim 3 in which said alkyl phosphite is tributyl phosphite.
- 60 5. A process for substantially reducing the mercaptan-sulfur content and odor of a mercaptan-containing petroleum naphtha boiling within the range of about 100°-400° F. which is substantially free from dissolved oxygen, which comprises intimately contacting said naphtha with tri-normal-butyl phosphite employing sufficient

amounts within the range of about 20 to 40 mols of phosphite per mol of mercaptan sulfur and for a time sufficient to reduce the mercaptan-sulfur content of said fraction to produce a doctor sweet product, said contacting being carried out at a temperature within the range of about 50° F. to the initial boiling point of the naphtha.

6. A process for substantially reducing the mercaptan sulfur content and odor of a mercaptan-containing petroleum fraction which comprises deoxygenating said fraction to effect the substantially complete removal of any free oxygen contained therein, and thereafter contacting said fraction with an organic phosphite from the group consisting of alkyl and cycloalkyl phosphites which is soluble in said feed stocks, employing sufficient amounts not less than about 20 mols of phosphite per mol of mercaptan sulfur and for a time sufficient to reduce the mercaptan sulfur content of said fraction to produce a doctor sweet product.

7. A process for substantially reducing the mercaptan sulfur content and odor of a mercaptan containing petroleum fraction which comprises purging said petroleum fraction with an inert gas to effect the substantially complete removal of any dissolved oxygen contained therein and thereafter intimately contacting said deoxygenated fraction with an organic phosphite from the group consisting of alkyl and cycloalkyl phosphites which is soluble in said hydrocarbon fraction, employing sufficient amounts not less than about 20 mols of phosphite per mol of mercaptan sulfur and for a time sufficient to reduce the mercaptan sulfur content of said fraction to produce a doctor sweet product.

8. A process for substantially reducing the mercaptan sulfur content and odor of a mercaptan containing petroleum fraction which comprises purging said petroleum fraction with an inert gas to effect the substantially complete removal of any dissolved oxygen contained therein and thereafter intimately contacting said fraction with an alkyl phosphite which is soluble in said petroleum fraction, employing sufficient amounts not less than about 20 mols of phosphite per mol of mercaptan sulfur and for a time sufficient to produce a doctor sweet product.

9. A process for substantially reducing the mercaptan sulfur content and odor of a mercaptan containing petroleum fraction which comprises purging said petroleum fraction with an inert gas to effect the substantially complete removal of any dissolved oxygen contained therein and thereafter intimately contacting said fraction with an alkyl phosphite which is soluble in said petroleum fraction, employing sufficient amounts not less than about 20 to 40 mols of phosphite per mol of mer-

captan sulfur and for a time sufficient to produce a doctor sweet product.

10. A process for substantially reducing the mercaptan sulfur content and odor of a mercaptan containing petroleum fraction which comprises purging said petroleum fraction with an inert gas to effect the substantially complete removal of any dissolved oxygen contained therein and thereafter intimately contacting said fraction with an alkyl phosphite which is soluble in said petroleum fraction, employing sufficient amounts not less than about 20 to 40 mols of phosphite per mol of mercaptan sulfur and for a time sufficient to produce a doctor sweet product, said contacting being carried out at a temperature within the range of about 50° F. to the initial boiling point of the petroleum fraction.

11. A process in accordance with claim 10 in which said alkyl phosphite is tributyl phosphite.

12. A process for substantially reducing the mercaptan sulfur content and odor of a mercaptan containing petroleum fraction which comprises purging said petroleum fraction with an inert gas to effect the substantially complete removal of any dissolved oxygen contained therein and thereafter intimately contacting said naphtha with tri-normal-butyl phosphite employing sufficient amounts within the range of about 20 to 40 mols of phosphite per mol of mercaptan sulfur and for a time sufficient to reduce the mercaptan-sulfur content of said fraction to produce a doctor sweet product, said contacting being carried out at a temperature within the range of about 50° F. to the initial boiling point of the naphtha.

13. A process for substantially reducing the mercaptan sulfur content and odor of a mercaptan containing naphtha fraction boiling within the range of about 100°-400° F. which comprises purging said petroleum naphtha with nitrogen to remove any free oxygen which may be contained therein and thereafter contacting said deoxygenated naphtha with tri-normal-butyl phosphite employing sufficient amounts within the range of about 20 to 40 mols of phosphite per mol of mercaptan sulfur and for a time sufficient to reduce the mercaptan sulfur content of said fraction to produce a doctor sweet product, said contacting being carried out at a temperature within the range of about 50° F. to the initial boiling point of the naphtha treated.

14. A process in accordance with claim 3 in which the alkyl phosphite is triethyl phosphite.
